UNITED STATES PATENT OFFICE

2,687,804

PROCESS AND APPARATUS FOR THE SPECIFIC GRAVITY CLASSIFICATION OF BULK SUBSTANCES UTILIZING FINELY GRANULATED SEPARATING MEDIA

Walter Vogel, Santiago, Chile

Original application July 23, 1947, Serial No. 763,121. Divided and this application August 25, 1952, Serial No. 306,232

Claims priority, application Switzerland September 11, 1946

11 Claims. (Cl. 209—483)

1

The present invention relates to the process and apparatus for the specific gravity classification of bulk substances utilizing finely granulated separating media. This application is a divisional of my prior application Serial No. 763,121, filed July 23, 1947, now patented under No. 2,612,269, dated September 30, 1952, and entitled Process and Apparatus for Specific Gravity Classification of Bulk Substances.

As indicated in said application, the separating media may be sand, gravel or other material reduced to suitable size in conjunction with apparatus effective to carry out the process.

More specifically the present invention relates to a process and apparatus for specific gravity classification of bulk substances in which the finely granulated media in the material to be separated flow in strata in an inclined stream greater than the natural angle of repose of the media and includes the discharge of the media and the material after first changing the direction of flow thereof at different relative velocities.

More particularly the invention relates to a dry process for separating solid materials in accordance with their specific gravities in a continuously moving stream of finely divided dry separating medium including feeding the material to be separated and the medium at one end of the zone disposed at an angle at least greater than the material angle of repose, changing the movement of the stream from a straight line flow to an arcuate flow tangentially to the straight line flow thereby imparting different relative velocities to the strata, separating the strata in accordance with the velocity thereof and removing the separated materials from the respective strata.

From German Patent 740,005 and as set forth in my above identified prior application, it is known to separate in a stream of finely granulated separating medium flowing in a trough means with the velocity of the different layers increasing from the lower to the upper layers. In such instances the stream with separating medium flows in the manner of a liquid in which, in accordance with the Archimedean principle, the heavier particles gradually sink to the bottom of the separating medium and the lighter particles are carried to the top. With such arrangements the different velocities of the advance movement of the finely granulated separating medium is achieved by the choice of angle of slope of the trough within which process is effected, as well as by adjustment of the blade or the like which divides the stream of separa-

2

ting medium and which blade is located at the discharge end of the trough. As pointed out in my prior application, such known processes do not accomplish satisfactory separation since the different velocities upon which principle the process is predicated, do not remain constant throughout the separating medium until the same reaches the discharge end.

Therefore, and consistent with the statement 10 of the invention, it is an object of the present invention to provide a process and an apparatus that eliminates such drawbacks in the prior art in a manner different from that embodied in my prior application Serial No. 763,121 now Patent No. 2,612,269 and which will permit adequate separation, the intensity of which can be regulated at will since the invention provides for the discharge of the different layers of separating medium at different velocities.

Specifically the present invention has for an 15 object to provide an improved process and apparatus for effecting specific gravity bulk classification in which separating media flows through a trough sloping at an angle at least greater than the natural angle of repose and by discharging the media in the form of a nappe so 20 that the layers more distant from the center of the arc traverse a greater distance in a given period of time compared with the layers closer to the center of the nappe.

In the accomplishment of the invention as 25 hereinabove set forth, increased velocity is imparted to the advance movement of the upper layers of the separating medium. However the present invention has for an object to provide for an inversion of this principle by increasing the velocity of the lower layers by the provision of a conveyor trough sloping upwardly at an 30 angle greater than the angle of repose in which the rate of feed of the lower layers is greater than the rate of feed of the upper layers.

The specific gravity classification of more than 35 two substances can very conveniently be accomplished by means of this invention and for this purpose two or more superimposed layers of separating media diminishing in specific gravity from the bottom to the top, are used simultaneously. If for example it is desired to obtain three products, two finely granulated separating media of diverse specific gravity are used, that is, an upper layer of lesser specific gravity over a lower layer of greater specific gravity. These layers advance in the trough simultaneously. At the discharge end of the trough the 40 light weight substance will be in the uppermost

layer, the middle weight substance will be in the intermediate layer, and the heavy weight substance will be in the lowermost layer, and same may be removed therefrom by screening each layer individually so as to recover the separating media for re-use in the trough aforementioned.

It is advantageous to use separating media having similar angles of repose. In some cases, in order to avoid intermingling of the layers, it may be expedient that the granulations of the separating medium of greater specific gravity be smaller than the granulations of the separating medium of lesser specific gravity. It may also be advantageous to have between the two layers of separating media of diverse specific gravities, an intermediate layer composed of a mixture of the adjoining layers, which mixture generally forms spontaneously during operation of the apparatus covered by this invention.

In order to maintain a constant separative intensity, the specific gravities as well as the angles of repose of the granulates of separating media should be maintained without variation. For this purpose the invention may be complemented with means for the continuous elimination of residues accumulating during the separating process, as well as for elimination of the secondary granulations that gradually accumulate in the separating media through screening thereof after the division of the diverse layers, which diminishes the purity thereof as a result of the inclusion of extraneous material.

For greater convenience it is possible to pass through a cleaning device, a partial stream of the separating medium used in any closed circuit. The method used may be, for example, either hydromechanical separation in a decantation machine, or pneumatic cleaning by means of air currents. If the hydromechanical method is used, the cleaned separating medium must be dried before being re-used in the separating process.

Many advantages are derived by using as a separating medium a material capable of being magnetized, the cleaning of which may subsequently be accomplished by magnetic separation, by merely passing a partial stream of the separating medium over an adequate magnetic field.

The purpose of this invention may also be achieved by using as a separating medium, hollow iron balls, in sizes and wall thicknesses proportionate to the specific gravity desired. It is likewise possible to use cast materials such as metallic alloys or glass, slag and ceramic materials, such as porcelain or materials held together by means of resins or other binding agents, including ferrous aggregates, in any given size required, and also, if necessary, spherical in structure. The use of such materials is particularly applicable in the separation of large bulk substances, inasmuch as in such cases it is thereby possible to select the most adequate proportion of the size of granulation of the separating media.

Finally, advantages may be derived by selecting as a separating medium a material whose hardness is greater than the hardest residue of the substance to be separated, so that during continuous contact thereof with the substance being separated in the trough, the residue as well as the secondary granulations will continue to disintegrate as a result of friction with the harder separating medium, and can then be separated therefrom by a simple screening operation. For this purpose the size of granulation chosen for the separating medium must be larger than the size of

the perforation or mesh of the screen used therefor. For example, in the separation of stock-piled bulk coal, the separating media used may be hollow cast steel or basalt balls, or solid glass balls 5 to 10 mms. in diameter. Thus a 12 mm. mesh screen may be used to recover the substance to be separated, and an 8 mm. mesh screen may be used to recover the separating medium from the residue, and if the screen be combined with a conveyor, it will be possible to return in a continuous manner, the screened separating medium to the principal circuit of the process effected by this invention.

The invention will now be described with reference to particular apparatus illustrated in the accompanying drawings, in which:

Figure 1 is a diagrammatic view in vertical cross-section of one form of the apparatus;

Figure 2 is a diagrammatic view in vertical cross-section of another form of the apparatus, and

Figure 3 is a diagrammatic view partially in vertical cross section illustrating the form of apparatus of Figure 1 embodied in a circuit including the return of the separating media to the troughs and the cleaning and drying of a partial stream thereof.

As illustrated in the drawing, the apparatus comprises a downwardly sloping covered trough 1 including a bottom 1a which trough is sloped at an angle greater than the angle of repose of the separating media. At the upper or head end of the trough is a feed hopper which includes funnels 2 and 3 for receiving the separating media and between these funnels there is provided a duct 4 through which is introduced the substance to be separated. The discharge end of the trough 1 terminates over roller 5 rotatably mounted on horizontal shaft 6 and driven by suitable transmission means including motor M. The bottom 1a of the trough is disposed in tangential relation with respect to the surface of the roller 5. The roller includes side extensions 7 of a height or radial distance from the center of shaft 6 such that they approximate the height of the side walls 5 of the trough 1. These side extensions 7 move very close, during rotation, to the side walls of the trough and as illustrated the same are partly covered by a conveyor belt 8 passing over rollers 9 and 10 constituting guide rollers, one of which is driven from the motor. As indicated this belt bearing on and moving with the rim or periphery of the side extensions 7 diverts the flow of medium and materials passing over the rotating roller 5. The action is such that the flow through the space defined by the surface of the roller, the inner surface of the side extensions and the conveyor belt is such that the superimposed layers of separating medium furthest removed from the surface of the roller advances at increased velocity. As the separating medium discharged by the belt passes over the lower pulley 10 it is divided into partial streams by one or more dividing blades 11 from which partial streams the diverse fractions of the substance to be separated are recovered individually. It is believed clear that the surface of the roller 5 impells the separating medium and additionally the conveyor belt 8 impells the medium so that in the flowing arcuate stream between the discharge end of the trough 1 and the guide roller 10 the action of the belt imparts increased velocity to the layer of medium furthest removed from the center of the roller 5 and closest to the surface of the belt.

In connection with separation effected by the

aforedescribed apparatus, the relative movement downward from each strata to that below following the angle of repose, fluidizes the sandy medium.

In connection with the arrangement shown in Figure 2 the apparatus embodied therein constitutes a kinematic inversion of the relationship shown in Figure 1. In Figure 2 the conveyor trough 12 is again a covered trough and slopes upwardly toward its discharge end at an angle greater than the angle of repose of the separating medium. At the lower end of the trough, that is at that portion preceding the rectilinear section, there is provided an arcuate plate 13 which in effect constitutes a feed hopper. This arcuate plate is spaced above the bottom 14 of the trough which is similarly arcuate at its lower end and between the plate and the bottom of the trough and upwardly along the trough moves the conveyor 15. The conveyor passes over spaced rollers 16 and 17, the roller 17 being at the bottom of the trough. Separating media is fed through inlet funnels 18 and 19 and the material to be separated is introduced through a duct 20 disposed between the funnels. This feed hopper relationship including the funnels, duct and the arcuate plate is such that the separating media are supplied at different rates of intensity to the rectilinear section of the trough in which separation is effected. A conveyor belt 15 may be composed of segments travelling along the bottom 14 of the trough and this belt advances the separating media containing the substance to be separated. If desired the belt may be eliminated and the material may be advanced up the trough by force feeding utilizing suitable pumps in conjunction with the funnels 18, 19 and the inlet duct 20. As indicated in the drawing the belt after passing over the upper pulley 16 on its return run passes over pulley 17 whose perimeter is above the arcuate portion of the bottom 14 and belt enters the feed hopper or arcuate portion between the plate 13 and bottom 14. The movement of the belt advances the lower layer of the separating medium in the trough at a higher velocity than the upper layer thus creating relative movements between adjacent layers and producing the same separating effect as is effected in the preceding arrangement with the result that the light-weight particles are carried to the top of the trough thereby effecting desired separation. After the strata of medium and the materials entrained therein pass over upper pulley 16 the stream is divided into partial streams by one or more adjustable blades 21 and from which partial streams the different fractions of the substances to be separated are recovered by individually screening these partial streams.

The arrangement of Figure 2 is of particular importance with regard to the classification of substances composed of large size granulations such as bulk coal. Generally speaking, bulk coal is classified by methods including hand picking which involve high costs and great loss of time when considering the output factor. With the present invention as disclosed in Figure 2, including the upwardly sloping trough, the structural relationship is provided which permits housing the entire plant in a rather low volume of space since there is sufficient vertical difference between the front feed and the upper discharge end to permit of installation of screens and other complementary equipment operable on the material for separating media and returning the same to the feed hopper. With this difference in elevation

such equipment can be installed in a substantially horizontal position. The means for returning the media to the troughs includes a hopper or bin 29 which receives media after it has passed through screen S. The discharge from this hopper is deposited on a conveyor belt 30 which delivers the media to another conveyor such as a bucket elevator 31. This elevator feeds the media to a conveyor 32 which is provided with blades, not shown, to divert the media from the conveyor belt to fall into the funnels 18 and 19. A trough 33 feeds the substance to be separated into the ducts 20.

In view of this low space factor and the fact that the process involved is a dry process that is very simple to operate, the present invention is particularly suitable for underground installation. In other words the apparatus of Figure 2 can be installed right in the mine in connection with the grading of coal thereby providing an arrangement in which only those sizes of coal that are of commercial significance can be elevated from the mine, eliminating the bringing to the surface of any useless residue.

In connection with both arrangements disclosed in Figures 1 and 2, it is obvious that the plant is to be completed by provision of means for continuously eliminating from a partial stream of separating medium, the residue and secondary granulations that gradually accumulate in the separating medium in the course of operation.

Such an arrangement is diagrammatically illustrated in Figure 3 in which cleaning devices include receptacles which receive the fractions of the substances being separated from the partial streams. In other words the blade 22 divides the discharge into partial streams which flow over suitable screens denoted at S' and the fractions of material to be separated pass off of these screens into suitable troughs or hoppers H for conveyance to their final destinations. The granulated medium that passes through the screen S' contains the residue and secondary granulations and this granulated medium is discharged into a bin or hopper 23 from which it passes to a conveyor belt 24 which carries it to a suitable elevator such as a bucket elevator 25 which carries it to another conveyor 26 arranged over the funnels 2 and 3. The conveyor that is above the feed funnels is provided with suitable scrapers, not shown, which divert medium into the respective hoppers and further divert a partial stream PS into a decantation machine 27 which removes residue and secondary granulations from the separating medium. The clean separating medium CSM passes through a drying drum 28 after it leaves the decantation machine and is returned to the conveyor belt 24 carrying the screened medium from adjacent the discharge end of the trough. The just previously described arrangement cleans only a partial stream of the medium. However it is obvious that the entire stream of separating medium passing through the screen at the discharge end of the trough may pass directly to the decantation machine thence through the drum and thence to a conveyor belt arranged above the feed hoppers from which it is diverted into the respective hoppers. Obviously instead of a wet process the separating medium from adjacent the discharge end can be cleaned by air current.

It is therefore clear that I have provided a process and apparatus for separating in a specific gravity classification of bulk substances utilizing finely granulated separating medium advancing

in an inclined trough, the feed of the material through the trough being such that the velocity of different layers of media in the trough is different and the stream flowing in a straight line through the trough is diverted to an arcuate flow tangentially to the base of the trough in which different strata of the stream have different relative velocities.

What I claim is:

1. A dry process for separating solid materials in accordance with their specific gravities in a continuously moving stream of finely divided dry separating media including feeding the material to be separated and the media at one end of a zone disposed at an angle sloping downwardly at least slightly greater than the natural angle of repose, changing the movement of said stream from a straight line flow to an arcuate flow tangentially to the straight line of flow, thereby imparting different relative velocities to the strata, separating the strata in accordance with the velocity thereof and removing the separated materials from the respective strata.

2. A process as described in claim 1 in which the stream is confined during its change of movement and the arcuate flow is of sufficient extent to divert the stream back toward its point of feed and discharging the stream in an arcuate flow prior to separation of the strata.

3. A dry process for separating solid materials in accordance with their specific gravities in a continuously moving stream of finely divided dry separating media including feeding materials to be separated and the media to one end of a separating zone, confining the material and media into a flowing stream of sufficient length and depth and at an angle greater than the natural angle of slope of the media permitting relative vertical components of movement in the strata in the stream following the angle of repose of the media to provide a fluidizing flow, imparting an arcuate movement to the stream in a tangential direction with respect to the straight line flow while simultaneously imparting increased velocity to one strata so that the strata with the materials to be separated entrained therein move at different relative velocities, discharging the strata while moving at different relative velocities, separating the strata into partial streams each containing material of different specific gravities and separating the material from the partial stream.

4. The process as defined in and by claim 3 in which the straight line flow is directed downwardly and the increased velocity is imparted to the upper strata.

5. The process as defined in and by claim 3 in which the major component of straight line flow is directed upwardly and the increased velocity is imparted to the lower strata.

6. The process as defined in and by claim 3 and including the return of separating media and reintroducing thereof into the feed end of the zone.

7. An apparatus for dry media separation of solid materials in accordance with their specific gravities including a trough disposed at an angle at least slightly greater than the natural angle of repose of the media and materials, vertically extending and longitudinally aligned feeding means at the upper end of the trough including means for feeding a mass of finely granulated separating medium to form a lower stratum, means for feeding finely granulated separating medium to form an upper stratum and means for feeding the materials to be separated interme-

diate said strata, the relative movement downward from each strata to that below following the angle of repose fluidizing the medium to entrain particles of material of different specific gravity in the different strata of medium, a member having a surface supported for movement in an arcuate path tangentially to the bottom of the trough so that the member receives strata from the trough and impells the same in an arcuate path imparting greater velocity to at least one strata, said strata discharging with different relative velocities, and means for separating the strata into partial streams in accordance with their specific gravities.

15 8. An apparatus as defined in and by claim 7 in which the trough slopes downwardly and the member imparts increased velocity to the upper strata.

20 9. An apparatus as defined in and by claim 7 in which the trough further includes a major portion being inclined upwardly at an angle greater than the natural angle of repose, said member comprises a conveyor belt, the trough includes a downwardly sloping portion preceding the upwardly sloping portion, and means supporting and guiding the conveyor belt so that a portion thereof follows an arcuate path disposed tangentially with respect to the bottom of both said trough portions, said belt moving throughout said upwardly sloping trough portion to impart greater relative velocities to the strata flowing upwardly with the lowermost strata having higher velocity.

25 10. In an apparatus for separating materials according to specific gravities, the combination of an inclined trough having upper and lower ends, said trough confining a flowing stream of finely granulated stratified separating medium and material to be separated therein and said trough being at least slightly more inclined than the natural angle of repose of said medium so that the mass of medium and materials flows downwardly, means at the upper end of the trough for feeding the materials to be separated and the medium to the trough, rotatable conveying means 30 at the lower end of the trough rotating in such direction as to continue the flow of said stream in an arcuate path, said conveying means receiving and carrying strata of said stream at different velocities corresponding to the radius of the circle they have to follow, said conveying means comprising a roller so disposed that the bottom of the trough is tangent thereto, disc means at the sides of said roller confining the flow, and a moving belt transverse to and adjacent said disc means and following an arcuate path receiving and conveying the medium therein around the roller axis.

35 11. In an apparatus for separating materials according to their specific gravities, a combination of certain means including separate longitudinally aligned channels including a central channel to receive and feed materials to be separated and additional channels adjacent thereto respectively receiving masses of finely granulated separating media, an inclined trough extending downwardly from said channels at an angle greater than the natural angle of repose of the media so that the materials and media flow therethrough superimposed strata, said trough 40 including an arcuate portion disposed tangentially with respect to the bottom thereof changing the direction of flow of the strata, said arcuate portion terminating in an upward inclination greater than the angle of slope and said trough continuing said upward flow a substantial dis-

tance, means for conveying the strata through said upwardly sloping portion and for imparting increased velocity to the lowermost strata, and means for discharging the strata at the upper end of the upwardly sloping portion in partial streams in accordance with their specific gravities and means for removing the media from said streams.
